UNITED STATES PATENT OFFICE.

ELWOOD BURTON NEWELL, OF GRAND RAPIDS, MICHIGAN.

COLLAR FASTENER.

Application filed January 14, 1928. Serial No. 246,691.

The present invention relates to collar fastening devices; and its object is, generally, to provide an improved device of that character for detachably connecting the adjacent edges of the outer flap of a turned-over collar.

This and any other and more specific objects hereinafter appearing are attained by, and the invention finds preferable embodiment in, the devices hereinafter particularly 10 described in the body of this specification and illustrated by the accompanying drawings, in which:—

Figure 1 is a front view of a collar fastening device;

15 Figure 2 is a front view of a portion of a collar, showing said device applied thereto; Figure 3 is a sectional view of a portion of said device taken on line 3—3 of Figure 1;

20 Figure 4 is a sectional view of a portion of said device and of the collar, taken on line 4—4 of Figure 2;

25 Figure 5 is a view of a modified construction of the collar fastening device carried on the inner side of the collar flap's edge portion; and

Figure 6 is a view of another modified construction carried on the inner side of the collar flap's edge portion.

In the embodiments of the invention illustrated by the drawings, my collar fastening device is employed to connect the adjacent edge portions 1, 1 of the turned-over outer flap 3 of a collar having the neck band 4 whose end tabs have button holes in which 30 a collar button 5 is received in the usual manner, the said device being carried on the inner side of such edge portions and extending under or behind the cravat or necktie (not shown) and serving to hold the same outwardly from the shirt front.

40 This device comprises a pair of keepers carried by said edge portions of the collar flap, the end portions of the keepers being secured to such edge portions, and the middle portions of the keepers being adapted to be drawn to mutually-approaching positions by connecting means comprising hook members 6, 6 adapted to removably engage the keepers, said hook members being detachably connected by suitable means, as the snap catch 7, one end 8 of which passes through a hole 9 in one of the hook members, its other end 10 detachably engaging in the hole 11 of the other hook member.

45 In the embodiment of the invention seen in Figures 1, 2 and 3, the keepers are elongated pointed pins 12 having end portions 13, 14 adapted to be thrust into the adjacent edge portions of said flap, and having also laterally-offset middle portions 15 in which the hooks 6 engage. These keepers 12 have heads 16, flattened in the plane in which lie the offset middle portions 15. It will be seen that the pressure of the connecting means 6, 7 draws the offset portions 15 to mutually-approaching positions, turning these keepers about their longitudinal axes, and causing the heads 16 to lie flat against the inner surface of the collar flap 3.

50 In the modified construction seen in Figure 5, the keepers are in form pins 12¹ anchored at their ends in the adjacent edge portions of the collar flap, the offset portions 15¹ of the pins being drawn toward each other by the connecting means; and in the construction shown in Figure 6 the keepers are flexible cords 12² secured at their ends and having slack middle portions 15² drawn toward each other by the connecting means.

55 It will be seen that the keepers being secured at their end portions to the flap 3 and having middle portions drawn by the connecting means toward each other, the hook members are prevented from slipping in the longitudinal direction of the keepers, and by 60 the pressure exerted thereon draw the edge portions 1, 1 toward each other thus maintaining the collar flap in unwrinkled position.

65 The collar flap being formed with an inwardly-turned hem part 17 stitched at 18, 19, as shown in Figure 5, the keepers 12, 12¹ may be inserted into said part 17 between the lines of stitching.

70 As shown, the flattened head 16 extends oppositely to the offset middle portion 15, so that the drawing of said offset portion by the connecting means causes the head to more readily lie against the inner surface of the collar's flap.

75 Portions 20 of the hook members are struck up therefrom to yieldingly hold the keepers in engagement.

80 The invention being intended to be pointed out in the claims, is not to be limited to or by details of construction of the particular embodiment thereof illustrated by the drawings or hereinbefore described.

I claim:

85 1. A collar comprising a neck band and a turned-over outer flap provided with keepers having their ends secured on the inner side.

of the adjacent edge portions respectively of the flap and having middle portions movable relatively to their secured ends into substantially the same plane by means for connecting said edge portions comprising hook members adapted to removably engage the middle portions of the keepers respectively.

2. A device for detachably connecting the adjacent edge portions of the turned-over outer flap of a collar, comprising: elongated pointed keepers having end portions adapted to be thrust into said edge portions respectively on the inner sides thereof, and having laterally-offset middle portions projecting from said inner sides; connected hook members adapted to removably engage the keepers respectively.

3. A device for detachably connecting the adjacent edge portions of the turned-over outer flap of a collar, comprising: elongated pointed keepers having end portions adapted to be thrust turnably into said edge portions respectively on the inner sides thereof, and having laterally-offset middle portions projecting from said inner sides and heads flattened in the planes of said offset portions; connected hook members adapted to removably engage the keepers respectively.

4. A device for detachably connecting the adjacent edge portions of the turned-over outer flap of a collar, comprising: elongated pointed keepers having end portions adapted to be thrust turnably into said edge portions respectively on the inner sides thereof, and having laterally-offset middle portions projecting from said inner sides and heads flattened in the planes of said offset portions and extending oppositely thereto; connected hook members adapted to removably engage the keepers respectively.

5. A device for detachably connecting the adjacent edge portions of the turned-over outer flap of a collar, comprising: keepers carried on the inner side of said edge portions respectively; connected members having flat body portions and hooks adapted to removably engage the keepers respectively and having also laterally spaced spring portions struck up from the body portions and extending oppositely-inclinedly therefrom and adapted to yieldingly hold the hooks in engagement with the keepers respectively.

In testimony whereof I have hereunto set my hand at Grand Rapids, Michigan, this 9th day of January, 1928.

ELWOOD BURTON NEWELL.
